CLAIM

The ornamental design for a gable top carton with angled corners, as shown and described.

DESCRIPTION

FIG. 1 is a front perspective view of a gable top carton with angled corners showing our new design;

FIG. 2 is a rear perspective view thereof;

FIG. 3 is a front elevational view thereof, the rear elevational view being a mirror image thereof;

FIG. 4 is a right side elevational view thereof, the left side elevational view being a mirror image thereof; and,

FIG. 5 is a top plan view thereof. The bottom of the gable top carton with angled corners is not a part of the claimed design.
